UNITED STATES PATENT OFFICE.

HUDSON A. TEDMAN, OF GALESBURG, ILLINOIS, ASSIGNOR TO WINSLOW BOILER & ENGINEERING COMPANY, OF CHICAGO, ILLINOIS, A CORPORATION OF ILLINOIS.

SAFETY DEVICE FOR OIL-BURNING SYSTEMS.

Application filed June 21, 1921, Serial No. 479,223. Renewed March 15, 1923.

To all whom it may concern:

Be it known that I, HUDSON A. TEDMAN, a citizen of the United States, residing at Galesburg, in the county of Knox and State 5 of Illinois, having invented certain new and useful Improvements in Safety Devices for Oil-Burning Systems, do hereby declare that the following is a full, clear, and exact description of the same, reference being had 10 to the accompanying drawings.

The invention relates to certain new and useful improvements in safety-devices for oil burning systems, and its primary object is to provide an improved apparatus for 15 safely producing a periodical flame from a mixture of air and atomized oil, and particularly means for automatically stopping the motor and the supply of fuel-oil to the burner in case the system fails to function, 20 as for example if the oil is not sufficiently atomized or the air supply is insufficient to provide a combustible mixture of oil and air, or if the ignition device does not ignite the fuel mixture.

25 In oil burning systems or plants using heavy grades of fuel-oil the oil is atomized and mixed with a supply of air to form the combustible mixture, which then is ignited by a suitable pilot light or electric spark, 30 and as these systems are usually intermittent in their heating action on the steam-generator or boiler, operating in accordance with the varying thermal conditions in the device being heated they are usually provided with means for periodically starting 35 and stopping the motor that drives the blower to supply the combustion air to the burner. However, these means do not otherwise control the system and if there is a failure 40 to produce or ignite the combustible mixture in the burner when an operative period occurs the fuel-oil continues to flow to the burner.

45 My invention provides improved means for automatically stopping the motor and flow of fuel-oil to the burner after a small quantity of this oil has passed to the burner under any condition that fails to produce a combustible mixture or ignite it, and so 50 prevents the accidental accumulation or waste of oil and the danger of explosion of the vapor arising from its natural vaporization in the restricted area of the fire-box or boiler-room.

55 In the accompanying drawings Fig. 1 is

a side elevation of a device embodying the features of my invention with a detail sectional view of a suitable fire-pot or burner; Fig. 2 is a detail view of the automatic trip-device, and Fig. 3 is a detail sectional view 60 of a form of electro-magnetic valve that may be employed.

In the drawings the reference numeral 1 indicates a combustion-chamber or fire-pot of suitable size and shape to conform to the 65 design of the associated steam-boiler, and to which fuel-oil is supplied by a fuel-pipe 2. A low-pressure blower 3 is mounted on a base-plate 4 and is provided with an air tube 5 which is connected at its outlet to 70 the fire-pot to furnish the combustion-supporting air; the air-tube preferably is divided at its outlet into two branches or conduits arranged tangentially to the interior of the fire-pot to deliver air to the pot in 75 two lateral streams on opposite sides of the nozzle 6 of the fuel-pipe 2. The conduits are suitably connected to the fire-pot, and these parts are provided with supports 7 and 8.

80 The blower is driven by an electric motor 9, which is mounted on the base 4 and is connected in an electric circuit 10 having any suitable source of current, and the circuit may be controlled to start and stop 85 the motor by any usual device such as the switch S, which may be operated by hand or any suitable means operating in accordance with varying thermal conditions in the device being heated. When fuel-oil is 90 supplied to the fire-pot through the pipe 2 and the motor is operated the blower or fan 3 delivers a sufficient quantity of air through the tube 5 to mix with the oil to form a readily combustible mixture and ensure 95 perfect combustion of the fuel so formed. The oil is discharged into the fire-pot from the nozzle 6 and preferably falls upon an inclined distributing and vaporizing plate 11 located near the bottom of the 100 pot by which it is broken up and atomized. The vaporized oil mixes with the inflowing air to form a fuel mixture which is readily ignited by a gas-burner 12 which is located under the plate 11 and is connected to a 105 suitable source of gas-supply by a pipe 13. The distributor plate is preheated by the lighting flame so that the initial oil falling on it is more quickly and thoroughly vaporized to accelerate its mixture with the air 110

and facilitate the lighting and burning of the fuel, and it is heated by the combustion of the fuel in the pot so that the oil falling upon it during the operation of the burner 5 is vaporized by it. The plate is preferably perforated to allow the oil to drip through to further break it up in contact with the lighting-flame, while the air passing into the pot also atomizes the oil; the fuel mixture 10 is readily ignited and continues to burn as long as the oil is supplied to the pot.

The bottom of the burner slopes or is inclined so that all oil that collects in it flows into a drain or sump 14 located at its 15 lowest point and having a drain pipe 15 extending in inclined position to discharge the oil out of the flame-zone or boiler with which the burner is associated. In case the burner fails to function, as for example, if 20 the oil is not sufficiently atomized or the air supply is inadequate or the gas-flame at the igniting burner is not burning when the fuel-oil is flowing into the pot, the oil will flow from the sump through the drain pipe 25 into a drip or overflow pan 16 which is located below the level of the sump. This pan is suspended on one arm of a bell-crank lever 17 pivoted on a bracket 18 on the base and having a trigger arm 19 to engage a 30 dog 20 on one end of a switch-lever 21 pivoted on a bracket 22 on the base and carrying an adjustable weight 23 at one side of its pivot and at its other side the movable element 24 of an electric switch 25 which 35 is located in the circuit supplying current to the motor so that the latter may be cut into and out of the circuit when the switch is operated. When the overflow is partly 40 filled with oil its weight or overload rocks the lever 17 to trip the trigger 19 and release the dog, whereupon the weight 23 moves the lever 21 to open the switch 25 to stop the motor.

This safety device may be set to operate 45 upon the accumulation of a slight quantity of oil in the pan and after it operates the pan is emptied and the parts are restored to their normal positions with the dog in engagement with the trigger-arm and the 50 switch 25 closed to allow current to pass to the motor when the main switch S controlling the circuit is properly set.

An electrically operated oil-valve is located in the fuel-oil line in order to shut 55 off all oil to the burner, and is operated by the electric current that operates the motor, the parts being arranged so that the valve is opened to permit the flow of oil to the burner as long as the safety device is in- 60 operative and is closed to positively shut off the supply of oil to the burner when that device operates. This valve may be of any suitable construction, and in the drawings I show a practical form in Fig. 3.

65 The case 26 of the electro-magnetic valve

shown is supported near the air-tube and preferably has a pipe 27 communicating therewith to furnish air to the interior and a perforated cap plate 28 to provide ventilation, so that circulation of air through the 70 case to cool its magnet is assured by the draft through the tube. The valve body is formed by a cup-shaped block 29 located in one end of the case and provided in its lower portion with the opposite inlet port 30 and 75 outlet port 31 screw threaded for the connection of the oil inlet pipe 32 and the outlet pipe 2 which pass through opposite sides of the case. The block is provided in its upper portion with a valve chamber 33 80 which is closed by a brass cover plate 34 attached to the inner end of the block by screws 35 as shown. The inlet port 30 opens into the chamber, and the central portion of the block projects into the chamber a short 85 distance to form an upward extension which is shouldered to receive a screen 36 which is held in place by a ring 37. The central extension of the block is provided with an oil passage 38 leading from the portion of 90 the chamber above the screen into the outlet port 31, and the upper end of this passage is formed as a seat for the valve 39 which is mounted on the stem 40. The plate 34 is provided with a guide-way for the upper 95 end of the valve stem, and a steel disk or armature 41 is carried by the stem, being located a suitable distance below the plate so that the armature and valve may move up to open the oil passage. The upper end of 100 the case is provided with a cross-bar 42 which carries a screw 43 by which a suitable laminated core 44 of an electro-magnet is supported in place adjacent the plate 34. The core is energized by the coils 45 which 105 are connected by the wires 46 to the circuit. When current flows through the circuit and the motor is operated the magnet is energized and the armature is drawn up toward the plate 34 to raise the valve from its seat 110 so that the oil will flow from the chamber 33 through the passage 38 to the outlet port and pipe 2. When the motor stops the magnet is de-energized and the armature and valve fall by gravity so that the latter closes 115 the passage to the oil outlet port.

The arrangement of parts for synchronously starting or stopping the motor and energizing or de-energizing the magnet to control the cut-off valve 39 may be varied; I prefer to positively and directly control this valve from the safety device itself, and so connect its magnet coils to the source of current through the switch 25. This organization stops the flow of oil when operative conditions in the plant are adversely affected, and prevents the waste of oil or its accumulation in the burner, which is always perfectly drained as the pan is arranged at a level below the sump to allow 120 125 130

the smallest quantity of oil to pass out of the fire zone and away from the boiler. Also, the cut-off valve is automatically included in the circuit by the resetting of the safety device which closes the switch 25 and when the motor is operated the valve is opened simultaneously and remains open to allow fuel-oil to flow to the burner as long as the plant operates to form and burn a combustible mixture, and when the safety device operates the valve positively cuts off the flow of the oil to the burner. The cut-off valve prevents the smallest quantity of oil from passing to the burner when the burner is inoperative either after a sustained run or between intermittent heating runs, while the drain comprising the oil sump and its discharge pipe prevents the waste of oil or its accumulation in the fire zone, and the safety trip ensures the automatic stopping of the motor and closing of the valve when operative conditions are so adversely affected that the fuel mixture is not produced or ignited. By adjusting the weight 23 toward the pivot 25 of its lever the safety device may be set to operate by the accumulation of a small quantity of oil in the pan, and by adjusting it away from the pivot the engagement of the trip members may be practically locked to hold the pan in position to catch all oil that may escape into the burner during a prolonged period of its inoperation.

I claim:

1. In a device of the class described, a burner having a fuel-oil line, a blower to feed air to the burner, an electrically controlled cut-off valve located in the oil line and included in an electric circuit, and automatic connections between the valve and the burner to permit the former to close the oil line when the burner fails to function.
2. In a device of the class described, a burner having a fuel-oil line, a blower to feed air to the burner, an electrically controlled cut-off valve located in the oil line and included in an electric circuit, a switch in the circuit, a drain for the burner, and an automatic safety trip between the drain and switch.
3. In a device of the class described, a burner having a fuel-oil line, a blower to feed air to the burner, an electric motor to drive the blower in circuit with a suitable source of power, an electrically controlled cut-off valve located in the oil line and included in the circuit, a switch in the circuit, a drain for the burner, and an overload trip-device between the drain and switch.
4. In a device of the class described, a burner having a fuel-oil line, a blower to feed air to the burner, an electrically controlled cut-off valve located in the oil line and included in a suitable circuit, a switch in the circuit, a drain for the burner, a

movable pan into which the drain discharges, and an overload trip-device between the pan and switch.

5. In a device of the class described, a burner having a fuel-oil line, a blower to feed air to the burner, an electric motor to drive the blower in circuit with a suitable source of power, an electro-magnetically controlled cut-off valve located in the oil line and included in the circuit, a switch in the circuit, a drain for the burner, a pan into which the drain discharges, a lever on which the pan is suspended, a second lever controlling the switch, and a trip connection between the levers.

6. In a device of the class described, a burner having a fuel-oil line, a blower to feed air to the burner, an electric motor to drive the blower in circuit with a suitable source of power, an electro-magnetically controlled cut-off valve located in the oil line and included in the circuit, a switch in the circuit, a drain for the burner, a pan into which the drain discharges, a lever on which the pan is suspended and carrying a trigger arm, a switch-lever carrying a dog to engage the trigger when the lever closes the switch, and an adjustable weight on the switch lever.

7. In a device of the class described, a burner having a fuel-oil line, means in the burner to vaporize the oil, a blower to feed combustion-air to the burner, means in the burner to ignite the fuel, an electrically controlled shut-off valve in the oil line, circuit connections from a suitable source of electric energy to the valve, a switch in the circuit, and connections between the burner and switch to automatically open the latter when the burner fails to function.

8. In a device of the class described, a burner having a fuel-oil line, means in the burner to vaporize the oil, a blower to feed combustion-air to the burner, an electric motor to drive the blower in circuit with a suitable source of power, an electrically controlled cut-off valve located in the oil line and included in the motor circuit, a switch in the circuit, and connections between the burner and switch to automatically open the latter to allow the valve to close the oil line when the burner fails to function.

9. In a device of the class described, a burner having a fuel-oil line, a hot-plate in the burner to vaporize the oil, a blower to feed combustion-air to the burner, an electric motor to drive the blower in circuit with a suitable source of power, an electrically opened cut-off valve located in the oil line and included in the motor circuit, a switch in the circuit, and connections between the burner and switch to automatically open the latter to allow the valve to close the oil line when the burner fails to function.

10. In a device of the class described, a burner having a fuel-oil line and lateral air-inlets, a blower to feed air to the burner, an electric motor to drive the blower in circuit with a suitable source of power, a hot-plate in the burner to vaporize the oil, an electro-magnetically controlled oil valve located in the oil line and included in the motor circuit, a switch in the motor circuit, a drain for the burner, and an automatic safety trip between the drain and switch.
11. In a device of the class described, a burner having a fuel-oil line and lateral air-inlets, a blower to feed air to the burner, an electric motor to drive the blower in circuit with a suitable source of power, a hot-plate in the burner to vaporize the oil, an electro-magnetically controlled oil valve located in the oil line and included in the motor circuit, a switch in the motor circuit, a drain for the burner, and an overload trip-device between the drain and switch.

In testimony whereof I affix my signature.

HUDSON A. TEDMAN.
